UNITED STATES PATENT OFFICE.

ELLIOTT D. MOORE, OF MOOREFIELD, OHIO.

DESIGN FOR A VEHICLE-WRENCH.

SPECIFICATION forming part of Design No. 26,618, dated February 9, 1897.

Application filed January 2, 1897. Serial No. 617,842. Term of patent 14 years.

To all whom it may concern:

Be it known that I, ELLIOTT D. MOORE, a citizen of the United States, residing at Moorefield, in the county of Harrison and State of Ohio, have invented and produced a new and original Design for Vehicle-Wrenches; and I do hereby declare the following to be a full, clear, and exact description of the same, reference being had to the accompanying drawing, forming a part thereof.

My invention relates to a design for a vehicle-wrench.

It relates to the entire configuration of the wrench, and especially to a wrench adapted to engage the inner face of the outer band and fit over the nut on the end of the spindle in such manner that the said nut may be turned off or on by revolving the wheel to the left or right.

My design relates particularly to the wrench as illustrated in the accompanying drawing, in which the figure illustrates a wrench embodying my design.

The leading features of my design appear in the following description.

A represents a tapering cylindrical head, in the smaller end of which is centrally located the rectangular recess B, the sides of

which have a common converging angle to the inner end of the said recess.

In constructing my device of wood I employ a metal shell C to prevent abrasion and splitting, the same being fitted in the recess B and accurately conformed to the shape thereof.

The handle of my wrench is formed integral with the circular head A at its largest end and longitudinally concentric therewith and consists of a substantially globular knob D, which is connected to the head A by the stem E, the flared ends of the said stem curving radially to meet the circumference of the said knob D and the head A.

Having thus fully described my invention, what I claim as new and useful, and desire to secure by Letters Patent of the United States, is—

The design for a carriage-wrench, substantially as herein shown and described.

In testimony whereof I affix my signature in presence of two witnesses.

ELLIOTT D. MOORE.
